AIR CONTROL DEVICE

Bernard M. Guthrie, Kokomo, Ind., assignor to
 Kingston Products Corporation, Kokomo, Ind.,
 a corporation of Indiana

Application January 10, 1941, Serial No. 373,896

8 Claims. (Cl. 137—152)

This invention relates generally to air control means, and more particularly to an automatic air control device for use in conjunction with domestic stoker apparatus.

One particular object of the invention is to provide a durable air control device which is particularly efficient in operation whereby to obtain uniform and substantially complete combustion of the fuel to be consumed.

Another object is to provide an air control device consisting of very few parts which can be economically manufactured and assembled on a production basis.

Other objects and advantages of the invention will be apparent after considering the description hereinafter set forth in conjunction with the drawing annexed hereto.

Referring to the drawing:

Figure 1 illustrates an application of the control device embodying the invention to the air supply apparatus of a conventional domestic heating plant, certain parts of which are shown in section;

Figure 2 is an end view in elevation of a part of the control device shown in Figure 3, certain parts of which are shown in section for the purposes of illustrating certain details of construction;

Figure 3 is a side view in elevation of the control device, with certain parts in section;

Figure 4 is a partial view of the damper and bracket unit used in conjunction with the control device;

Figure 5 is a section taken substantially on line 5—5 of Figure 3;

Figure 6 is a section taken substantially on line 6—6 of Figure 2 showing certain details of construction; and

Figure 7 is a partial view, partly in section of the stop for limiting movement of the damper, including related structure.

The air control device is particularly designed and constructed to prevent an excessive volume of air under pressure from passing into the retort or fire pot when the fuel is not in the proper condition or state to receive such volume, particularly at a time when the fuel has become quite porous by burning during the inactivity of the blower and stoker. The admission of a vast volume of air under pressure from the blower at such a time has a tendency to disrupt the fuel bed and cause the scattering of fly ash, and when new fuel is added the fire is temporarily smothered. In other words, the device is so constructed and arranged that the proper volume of air is

admitted at the proper time whereby to obtain satisfactory combustion of the fuel.

It is therefore manifest that some form of automatic means is desirable for controlling the volume of air admitted to the retort in accordance with the rate of fuel delivery whereby to obtain efficient results.

Considering now the structure illustrated in the drawing, particularly Figure 1, numeral 1, generally designates a stoker and 2 a heating unit. The stoker is provided with a hopper 3 and a blower 4, and the heating unit with a retort or fire pot 5 including an air chamber 6 adjacent the retort. A conveyor 7, preferably of the screw type, is disposed in a conduit 8 for conducting a predetermined amount of fuel from the hopper through the conduit into the retort at a predetermined rate, and a conduit 9 provides a passage through which the air from the blower is directed under pressure into the air chamber 6 and out through the tuyères 10 into the retort 5 whereby to supply air to the fuel conveyed to the retort.

The above described structure may be of the conventional type, and the air control device 11 constituting the present invention is adapted to be disposed at some desirable point within the air conduit or duct 9 for automatically controlling or regulating the volume of air admitted to the fuel, and includes, among other things, a tubular housing 12 which carries a damper 13, and an element 14, preferably in the form of a dashpot, whereby to retard movement of the damper 13 within the housing 12.

The air control device 11 is designed and constructed so that it can be easily and quickly installed, and this is preferably accomplished by inserting the ends 15 of the housing into the sections of the conduit 9, the abutments 16 adjacent the ends providing stops engageable with the ends of said sections whereby to predetermine the position of the housing. The stops 16 surround the housing and to some extent assist in preventing the escape of air from the conduit, particularly when a back pressure develops. Obviously the housing may be cemented or otherwise sealed in place. The housing when properly installed within the conduit 9 actually forms a part, extension, or continuation thereof in order that the air may flow through the conduit without being interrupted other than by the damper 13 above referred to.

The housing may be constructed of any desirable material, but is preferably die cast, and made rectangular in cross-section so as to corre-

spond with the cross-section of the conduit or flue 9. The housing includes, among other things, parallel side walls 17 and 18, and top and bottom walls 19 and 20, respectively.

An auxiliary casing or hood part generally designated 21 is preferably provided adjacent the upper extremity of the side wall 17 of the housing 11, with its longitudinal axis disposed in spaced apart parallel relation to the longitudinal axis of the housing. This casing or hood 21 is of a size sufficient to freely receive the damper retarding mechanism or dashpot 14, above referred to. The hood includes, among other things, a top wall portion 22 which is joined to a side wall portion 23 by a radial portion 24, and end wall portions 25 and 26. As clearly shown, the top wall 22 is disposed slightly below and parallel to the top wall 19 of the housing, and the side wall 23 is disposed in spaced apart parallel relation to the wall 17, the latter being common to both the housing and hood. The hood may be open at its lower extremity, as shown, and the end walls 25 and 26 preferably terminate short of the ends of the housing.

The upper extremity of the hood adjacent one end is preferably provided with an upwardly extending hollow enlargement or bulge 27, the arcuate or curved top wall of which is arranged approximately flush with the top wall 19 of the housing 12. The side wall 11 of the housing also provides a side wall for this enlargement, and the other side wall 29 of said enlargement is preferably provided with a more or less centrally disposed inwardly extending generally circular boss portion 30, and a laterally projecting portion 31 located at one side of the boss in parallel relation to the end walls 25 and 26 of the auxiliary casing or hood. The boss and projection are preferably integrally connected to the arcuate top wall 28 and also to each other by a connecting portion 32. These portions are so constructed that same are reinforced by each other and at the same time brace portions of the enlargement 27. The projection or depending portion 31 provides a stop whereby to limit movement of the damper in one direction and will be discussed more in detail later.

The boss 30 is preferably provided with a threaded hole 33, shown in Figures 2 and 7, which receives a screw 34 having a conical bearing point 35 providing one of the bearings for the damper 13.

The upper extremity of the side wall 18 of the housing is provided with an outwardly extending generally cylindrical boss 36, somewhat similar to the boss 30, and has a threaded hole which receives a screw 37 having a conical point 38 whereby to provide the other bearing for the damper 13. These set screws 34 and 37 may each be provided with a slot so that the screws may be easily adjusted by a screw driver or other tool, and lock nuts 39 may be used to lock the screws in place after they have been adjusted. An aperture 40 is provided in the side wall 17 of the housing in line with the threaded holes in the bosses 30 and 36.

The damper 13 is preferably of channel shape and includes a bottom wall 41 and relatively short side walls 42, and is of a size to substantially or completely close the air passage formed by the housing 12, when moved from its normal angular full line position to its lowermost dotted line position, as illustrated in Figure 3. If found desirable, the damper may be formed otherwise than illustrated, for example, the lower

extremity thereof may be arranged at an angle with reference to its upper extremity, in order to possibly better receive the air that is being forced through the conduit.

5 A bracket generally designated 43 is secured adjacent the upper end of the damper 13 by spot welding, or other desirable means, and includes a relatively large flat base portion 44 which engages the bottom wall of the damper in order 10 to reenforce same to some extent. One extremity of the base portion 44 is provided with a lug 45 which extends outwardly substantially at right angles with reference to said base portion, and the other extremity of the base is provided with 15 a lever or arm 46 which extends outwardly in the same general direction as the lug 45, and at an acute angle with reference to the base. This arm 46 is arranged in an offset relation with respect to the base portion 44 by means of an extension 47, which extension is a continuation of said base portion. The arm and lug are arranged in spaced apart parallel relation to each other and to the side walls of the housing 12. That portion of the arm adjacent the extension or 20 continuation 47 of the base, and the lug 45 are each provided with a conical bearing seat 48 whereby to receive the points of the set screws 34 and 37 above referred to. The free end of the lever 46 is provided with a hole 49.

30 Thus far it should be apparent that the damper may be centered within the housing 12 by means of the set screws 34 and 37, and that the extension 47 projects through the aperture 40 in the wall 17 and into the hood and enlargement 27, 35 and is in connection with the means 14 for retarding movement of the damper. It will also be apparent that the depending lever arm 46 when moved to a predetermined position to the left by the pressure of the air against the damper 40 will engage the stop 31 for the purpose of limiting the movement of the damper in one direction.

The device for retarding movement of the damper is preferably of a size to fit substantially 45 entirely within the confines of the hood 21 and, includes among other things, a tubular cylindrical metal member 50, closed at one end by a plug 51 permanently secured in place by a pressed fit or otherwise whereby to completely seal said end. This plug has a cylindrical portion 52 and a flange 53 which tightly engage the inner wall and the end wall of said tubular member, respectively. The member 50 and plug 51 are preferably made of die cast material.

55 One side of the portion 52 is preferably provided with an axially extending spindle 54 which projects through a generally rectangular hole 55 provided in the end wall 25 of the hood. This spindle is made cylindrical as indicated at 60 56 near the portion 52, and the remainder is preferably flattened on opposite sides, the unflattened portions being threaded whereby to engage a knurled nut 57. One side of the nut is adapted to cooperate with a scale 58, provided on the flattened inclined side open to view. This arrangement prevents rotation of the member 50 and spindle 54, and provides means for adjusting the angle of the damper to suit various conditions. More specifically, the nut may be rotated so that one face thereof will register with 65 numeral 2 on the scale, in which event the damper would nearly close the air passage, and very little air pressure would be required to pivot the damper. If the nut were rotated to register with numeral 6, the damper would be elevated.

and a greater pressure would be required to operate it. In order to prevent tilting of the element 50 when the device is operating, the end wall 25 of the hood is preferably provided with an inwardly extending boss 59 through which the spindle 54 extends.

The other side of the portion 52 of the plug 51 is provided with an axially extending centrally disposed tubular protuberance 60, within which one extremity of a resilient element, in the form of a tightly coiled spring 61 is permanently secured by depressing portions of the protuberance against the spring. The other end of the spring is similarly permanently secured within a central round tubular protuberance 62 provided on a connecting piston member or link generally designated 63. This piston is preferably made of die cast material, and includes the protuberance 62 just referred to; an annular portion 64 having a concave groove or cove 65 in its periphery; and an axially extending round spindle 66 which is preferably bifurcated at its free extremity to receive the free end of the arm 46 secured to the damper 13. A cotter pin 67 or other desirable means extends through holes provided therefor in the spindle 66, and through the hole 49 in the lever arm 46 whereby to pivotally connect the element 63 with respect to the arm, as most clearly shown in Figure 3.

When air under pressure is forced through the housing 12 in the direction indicated by the arrow in Figure 3, the damper will move downwardly to some extent as indicated by the dotted lines, expanding or stretching the spring 61, and when the air pressure diminishes or the blower is shut off, a resilient cylindrical piston ring 68 functions to ease the return movement of the damper back to its elevated full line position. The piston ring 68 is preferably constructed from soft rubber or the equivalent in the form of a generally tapered cylinder, the larger extremity of which is preferably slightly flared or belled while the opposite extremity is provided with an internal annular convex bead portion 69 which snugly fits within the cove or groove 65 of the piston 63. The outer surface of the belled or larger extremity of the cylindrical ring is adapted to frictionally engage the inner wall of the element 50, and when the air pressure in the system diminishes the piston is moved inwardly due to the action of the spring 61 causing the compressed air within the chamber formed by the member 50, to be expelled through a port 70 provided in the wall of the member 50. Accordingly, it is apparent that the dashpot acts as a check, and that the spring and ring function to counteract each other during the swinging movements of the damper.

Having thus described my invention, it is obvious that various modifications may be made in the same without departing from the spirit of the invention; and, therefore, I do not wish to be understood as limiting myself to the exact form, construction, arrangement, and combination of parts herein shown and described.

I claim:

1. A tubular housing adapted to form part of a fluid conduit, a damper movably disposed in said housing, elongated stationary means provided on said housing including a side wall and an end wall, bracket means pivotally connecting said damper to one of the walls of said housing and to said side wall, means connected to said bracket for progressively retarding movement of said damper, and an adjustable connection connecting said last-mentioned means to said end wall.

2. In combination: a fluid conduit, a housing

interposed in said conduit and forming a part thereof, a wall integral with and arranged in spaced relation to a wall of the housing, a damper disposed in said housing, a bracket for supporting said damper having a bearing on one of the walls of the housing, an extension of said bracket projecting through another wall of the housing and having a bearing on said integral wall, a lever carried by said bracket, and means for progressively retarding movement of the damper having a part connected to said lever and a part to a portion of said integral wall.

3. Means for assisting in the control of the flow of a fluid through a conduit including, a housing, a wall integral with and disposed in spaced apart relation to a first wall of the housing, a second wall arranged transverse to said integral wall and to said first wall of said housing, a damper disposed in said housing, a bracket supporting said damper having a bearing on said first wall, said housing having another wall between said integral wall and said first wall, an aperture provided in said another wall, said bracket being provided with an extension projecting through said aperture and having a bearing on said integral wall, a lever carried by said bracket, and a dashpot having a part connected to said lever and a part to said second wall for progressively retarding movement of the damper.

4. Means for assisting in the control of the flow of a fluid through a conduit including, a housing having a first wall, a wall integral with and disposed in spaced apart relation to said first wall, a second wall arranged transverse to said integral wall and to said first wall of said housing, a damper disposed in said housing, a bracket for supporting said damper having a bearing on said first wall, said housing having another wall provided with an aperture, said bracket being provided with an extension projecting through said aperture and having a bearing on said integral wall, a lever carried by said bracket, a dashpot having a part connected to said lever for progressively retarding movement of the damper, and a part to said second wall, and abutment means provided on said integral wall for limiting movement of the damper in one direction.

5. In an air control device, a housing unit including first, second, and third walls arranged in generally spaced apart parallel relation, a damper disposed between said first and said second walls, an aperture provided in said second wall, a bracket supporting said damper projecting through said aperture and having bearing on said first and third walls, connection means carried by said bracket, and means for progressively retarding movement of the damper having a part connected to said connection means and a part connected to the housing.

6. In an air control device, a housing unit generally rectangular in cross-section including a pair of substantially parallel walls, a damper disposed between said walls, a supplemental wall arranged in spaced apart parallel relation to said pair of walls, an aperture provided in one of said pair of walls, a bracket supporting said damper having a bearing on said supplemental wall and projecting through said aperture and having a bearing on the other of said pair of walls, means arranged between said other wall and said supplemental wall and connected to the bracket for progressively retarding movement of the damper, and means providing an adjustable connection between said retarding means and a part of the housing.

7. In an apparatus of the character described, a

tubular housing, a hood provided adjacent one side of the housing, a damper movably mounted in said housing, dashpot means for retarding the movement of the damper arranged in the hood alongside said housing and operatively connected to said damper, said dashpot means including a cylinder, piston means movable in the cylinder, rigid means projecting from the piston means and rigidly connected thereto and means connecting the rigid means to the damper so that on movement of the damper the rigid means will be caused to move in a path at an angle to the axis of the cylinder, said piston means being so constructed and arranged that at least a portion thereof may tilt relative to said rigid means while 15

maintaining contact with the walls of the cylinder.

8. In an air control device, a housing unit including first, second, and third walls arranged in generally spaced apart parallel relation, a damper disposed between said first and said second walls, an aperture provided in said second wall, a bracket supporting said damper projecting through said aperture and having bearing on said first and third walls, connection means carried by said bracket, and dashpot means for progressively retarding movement of the damper having a part connected to said connection means and a part connected to the housing.

BERNARD M. GUTHRIE.
